his attorney.

UNITED STATES PATENT OFFICE.

ALBERT FRANK FIFIIELD, OF ST. CATHARINES, ONTARIO, CANADA, ASSIGNOR TO THE AMERICAN FORK & HOE COMPANY, OF CLEVELAND, OHIO, A CORPORATION OF OHIO.

RAIL JOINT.

Application filed November 11, 1927. Serial No. 232,543.

This invention relates to an improvement in rail joint construction and relates more particularly to wear compensating means for old or worn rail joints, whereby rail joint bars which have become worn by movements of the rail in the joint and which otherwise are sufficiently strong to meet the requirements of practical use may continue to be employed for efficient use in connection with either old rails or new rails.

The wear in a rail joint is found to be greatest at the ends of the rails due to contraction and expansion of the rails and due to the increased motion of the rails under varying speed and load conditions. The hammering down of the rail ends ultimately results in wear, particularly of the rail joint bars at the undersides of the rail heads and this wear is much increased immediately at the ends of the rails.

I am aware that there has been proposed for use a shim construction which permits the fitting of the same in place between worn portions of a rail joint side bar and the undersides of the rail head and which will permit continued use of the rail joint side bars regardless of the amount of wear had on their upper inner surfaces. These prior shims are broadly of two general types, which I might term "whole" shims and "half" shims. Shims of the "whole" type, are tapered both ways from their mid-portion, which are disposed adjacent the ends of the rails, one of such shims being placed at each of the two sides of the joined rails. Whereas the "half" type shims are tapered in one direction only and double the amount of such shims are required.

The present invention relates particularly to improvements in "whole" type shims and has for an object the provision of a shim of the "whole" type which may be accurately positioned relative to the rail joint ends and without liability of displacement therefrom during use of the rail joint.

Another object of my invention is to provide an improved rail joint shim of the "whole" type, in which the breakage, if such occurs due to operation of the joint, will not result in longitudinal movement of the shim along the joint, such as would impair the usefulness of the shim as a wear compensating means.

Another object of my invention is to pro-

vide a shim for rail joints in which breakage of the shim incidental to the use of the rail shim is limited to a predetermined portion of the shim.

Another object of my invention is to provide a shim having integrally associated therewith means adapted to cooperate with the rail joint in such a way as to permit either equal or variable amounts of compensation for wear occasioned by the two rails of a joint.

Other objects of the invention and the invention itself will become apparent by reference to the following description of certain embodiments of my invention and in which description reference will be had to the accompanying drawings, illustrating the said embodiments and in which drawings:

Fig. 1 shows in transverse section an embodiment of my invention comprising a section of rail with the side bars bolted thereto and interposed wear compensating shims between the heads of the side bars and the underside of the rail head flanges;

Fig. 2 shows a perspective view of a "whole" type shim embodying my invention, two of which are adapted to be disposed in a rail joint, as shown in Fig. 1;

Fig. 3 is a perspective view of a modified form of the embodiment of Fig. 2;

Fig. 4 is a perspective view of another embodiment of my invention;

Fig. 5 is a section taken on the line 5—5 of Fig. 4;

Fig. 6 is a side elevational view of the shim of Fig. 2;

Fig. 7 is a side elevational view of the rail joint of Fig. 1 with a rail joint shim, as illustrated in Figs. 2 and 6; shown therein and with the side bar removed so as to permit a direct view of the shim; also in this figure, in dotted lines, is shown an alternate positioning of the shim for a special purpose subsequently herein referred to.

Referring now first to the embodiment of my invention illustrated in Figs. 2 and 6, and as applied to a rail joint, as illustrated in Figs. 1 and 7, the wear compensating shim of the said figures, comprising a preferred embodiment of my invention, is of angle formation having an apron part 1, adapted to be disposed between the inner side of the joint bar 2 and the rail web 3, and an upper flange part 4. The shim is preferably made

thickest along the line $x-x$ of Fig. 6 and tapers therefrom in both directions until the ends 5 and 6 of the shim are reached whereat the shim is of preferably minimum thickness. I preferably make the shim of my invention of this tapered formation.

In rail joints of the conventional type, one employing side bars shown at 2, a plurality of bolts, two of which are shown at 7 and 8 10 and others such as 9 and 10, to secure the side bars in place in clamping engagement with the rails. These bolts project through apertures 11 provided by piercing the rail web 3 at spaced intervals and I therefore provide spaced depending portions or prongs 14 15 and 13 integrally formed with the apron 1, of the shim projected below the level of the bolts and adapted to be placed intermediate those bolts 7 and 8 which are placed nearest 20 the ends of the rails 15 and 16.

The disposition of the prongs 13 and 14 with their outer lateral edges 17 adapted for engagement with the bolts 7 and 8 upon endwise movement of the shims and of the lower 25 edges 18 of the apron disposed for engagement with the upper surface of the bolts 7 and 8 accomplishes a substantial uniformity of positioning relative to the spaced ends of the rails 15 and 16 and prevents displacement, 30 especially in the longitudinal direction of the shims relative to the other parts of the rail joint. Except for such a provision, the thickest part X, Fig. 7, of the shim which in the figure is shown as being disposed adjacent the space 20 between the rails, might be shifted to occur remote therefrom in one direction or other and which might not coincide with the points of greatest wear of the rail joint side bar 2, for which the greatest 35 thickness of shim is adapted to compensate.

At the same time, however, it is sometimes found that in rail joints, particularly wherein the rails are used by trains traveling mostly 45 in a single direction, as in "one-way" traffic, that the rail of the joint, such as the rail 15, termed the "receiving" rail which is traversed by the wheels of the train last is caused to pound more vigorously than the rail 16 at the 50 approach side of the joint and consequently a larger crevice is produced below the rail head 21 of the rail 15, in such a case upon the upper surface 22 of the rail joint bar, and therefore it is desirable that a rail joint shim 55 of the type illustrated in Fig. 6 be shiftable longitudinally of the rails to the dotted line position illustrated in Fig. 7, whereby the point of greatest thickness X may be moved longitudinally of the rails to a position indicated by the arrow at X-X.

In this case the end of the shim underlying the rail head of the rail 16 will have its end edge 23 moved longitudinally of the rail 16 to the dotted line position 23', and the prongs 65 13 and 14 will necessarily be placed as illus-

trated at 13' and 14' in the dotted line representation of the prongs, when the shim is moved to a position where the thickest point underlies the point $x-x$, Fig. 7. In such alternate dotted line position of the shim, 70 the prong positioned at 13' is adapted for engagement by its inner edge with the outer lateral surface of the bolt 8 to prevent longitudinal shifting of the shim from its said alternate position, illustrated by dotted lines, 75 toward its solid line position.

Sometimes, as has been previously stated, the movement of the rails effects a breakage of the shim and I find that the provision of the notches N, Figs. 2, 6 and 7 and the inverted V-shaped notch N', Fig. 3, and the groove extending along the line of the face of the shim, shown in Fig. 5, at N'', effects the purpose of causing the breakage to occur along a line of cleavage starting approximately at 85 the point x , Fig. 7, and continuing transversely across the shim to the upper edge 27 of the notch N in the case of those constructions illustrated in Figs. 2, 6 and 7 and to the axis 28 of the notch N' of Fig. 3 and in the case 90 of the Figs. 4 and 5, the breakage will occur along the lines N'', that is, in that line indicated in Fig. 4.

In all of the above cases the terminating portion of the line of breakage lies within 95 the prongs 13 and 14 and may for instance be along the waved dotted line shown at y, Fig. 7. This is more true because of the shim being weaker in transverse sections between these prongs than it is in portions including 100 the prongs where the shim is of greater width, and also because the greatest stresses are exerted intermediate the prongs.

In such a case should breakage occur between the prongs 13 and 14, the shims will 10 continue to operate and will be retained lengthwise of the joint in their correct positions by the bolts 8 and 7 engaging the prongs.

In Fig. 3, where the notch N', is substantially in the form of an inverted V, with its 11 apex at 28, the breakage will naturally be had between the notch apex 28 and the point x which is disposed intermediate the rails. In the embodiment of Fig. 4, the groove N'' so weakens the mid portion of the shim that 11 upon breaking stresses being communicated by the ends of the rails, the breakage will occur along the line 5-5 of Fig. 4 and the shim will be as in the previously described shims of Figs. 2 and 3, divided into two half-shim 12 sections each having a depending apron with lateral outer edges 17', corresponding to the edges 17 of the prongs 13 and 14 of Fig. 7, in engagement with the bolts 8 and 7. The plates engaging the lateral edges 17' will 12 prevent longitudinal displacement of the thus accidentally formed shim-halves.

Having thus described my invention in several embodiments, I am aware that several departures may be made from the em- 13

bodiments herein illustrated and described but without departing from the spirit of my invention.

I claim:

5. 1. A shim for worn rail joints comprising a body of angular cross-section progressively thickened from its ends toward its mid section adapted to fill the worn portions between the end side of the rail heads and the joint bar, said shim being so formed as to be more susceptible to transverse breakage in its thickened mid portion than in portions relatively remote thereto.
10. 2. A shim for worn rail joints comprising a body of angular cross-section progressively thickened from its ends toward its mid section to provide for the filling of the worn portions between the under side of the rail heads and the joint bar, and comprising a depending apron adapted to be positioned between the rail joint bolts nearest the ends of the rails to prevent longitudinal displacement of the shim in the joint, said shim being so formed in its mid portions relative to the 20 formation in portions longitudinally adjacent thereto as to insure transverse breakage in the mid portions upon the shim being subjected to transversely impressed breaking stresses due to movement of the jointed rails 30 in use.
15. 3. A wear compensating means for rail joints comprising a metallic shim member progressively thickened in the direction of its length toward its center adapted to be interposed between the joint bar and the under sides of a pair of rail heads to compensate for wear between the under sides of the rail heads and the joint bar, said shim comprising a depending apron positioned between the rail joint bolts nearest the ends of the rails to prevent longitudinal displacement of the shim in the joint, the shim and apron being weakened in their mid portions relative to adjacent portions.
25. 4. A wear compensating means for rail joints comprising a metallic shim member of angular cross-section, progressively thickened in the direction of its length from its ends to its middle and comprising a pair of spaced apron prongs each positioned adjacent a different one of the pair of rail joint bolts disposed nearest the ends of the rails joined and engageable with said bolts to prevent longitudinal displacement of the shim in the joint.
30. 5. A wear compensating means for rail joints comprising a metallic shim member of angular cross-section, progressively thickened in the direction of its length from its ends to its middle and comprising a pair of spaced apron prongs each positioned adja-

cent a different one of the pair of rail joint bolts disposed nearest the ends of the rails joined and engageable with said bolts to prevent longitudinal displacement of the shim in the joint, said shim being transversely more susceptible to breakage intermediate the prongs than in longitudinally contiguous portions.

6. A wear compensating means for rail joints comprising a metallic shim progressively thickened from each end in the direction of its length toward the center of the joint, and comprising depending portions adjacent the middle portion adapted to engage with the joint securing bolts disposed nearest the center of the joint to prevent longitudinal displacement of the shim in the joint.

7. A shim for worn rail joints comprising a body of angular cross-section having an angular section tapering in thickness from an end toward the center of the joint and adapted to be disposed between the under side of the head of a rail end and the upper side of a joint bar and comprising a depending apron adapted to contact with a joint bolt to restrict the shim from longitudinal movement in the joint.

8. A wear compensating means for worn rail joints comprising a shim section tapering in thickness in the direction of its length toward the center of the joint and comprising a depending portion adapted to engage a securing bolt of the joint to restrict longitudinal movement of the shim in the joint.

9. A wear compensating means for rail joints comprising a metallic shim section tapering in thickness from its mid portion toward both its ends and the thickened portion being adapted to be disposed beneath the ends of adjacent rail heads above the upper edge of the joint bar to compensate for wear between the opposing surfaces of the heads and the joint bar, and comprising a depending portion engageable with relatively immovable portions of the joint to restrict movements of the shim in a longitudinal direction relative to the ends of the rails.

10. A wear compensating means for rail joints comprising a metallic shim section adapted to be disposed beneath the ends of adjacent rail heads above the upper edge of the joint bar to compensate for wear between the opposing surfaces of the heads and the joint bar, and comprising an integrally depending portion engageable with relatively immovable portions of the joint to restrict movements of the shim in a longitudinal direction relative to the ends of the rails.

In testimony whereof I hereunto affix my signature this fifteenth day of October, 1927.

ALBERT FRANK FIFIELD.
